CAR TRUCK

Leo A. Lehrman, Chicago, Ill., assignor to American Steel Foundries, Chicago, Ill., a corporation of New Jersey

Application June 21, 1943, Serial No. 491,599

26 Claims. (Cl. 105—197)

My invention relates to railway car trucks and more particularly to a truck incorporating a ride control device by means of which frictional control is afforded of the oscillation of the bolster supporting coil spring group.

An object of my invention is to design a ride control truck incorporating a snub-up device which operates to develop a greater amount of friction during upward movement of the bolster than that which is developed during downward movement thereof.

A specific object of my invention is to design a truck such as above described wherein friction shoes are pocketed in opposite sides of the bolster and in wedge engagement therewith, said shoes being urged into wedge engagement with the adjacent side frame columns by means of at least one resilient unit including a compressed spring and means for transmitting reaction of said spring to the shoes and the bolster, said means including a bolt and nut assembly affording adjustable compression of said spring.

Another object of my invention is to provide a stabilizing means in a freight car truck such as above described wherein adjusting means to compensate for wear of the friction surfaces is easily accessible without removal of any single part of the stabilizing means or disturbing any other part of the truck.

My invention comprehends friction shoes of novel form, certain of said shoes comprising bolt openings therethrough interrupting the wedge surfaces thereon, and other of said shoes comprising wedge surfaces angularly disposed with respect to abutment surfaces for an associated actuating member, said surfaces being crowned to afford rocking movement of the shoes against the bolster wedge surfaces and against the actuating member.

In the drawings,

Figure 1 is a fragmentary side elevation of a railway car truck comprising one embodiment of my invention.

Figure 2 is a fragmentary top plan view of the structure shown in Figure 1 with the side frame shown in section through one of the columns, and Figure 3 is a sectional view taken substantially in the vertical longitudinal plane indicated by the line 3—3 of Figure 2.

Figures 4 to 6 inclusive show the novel friction shoe utilized in Figures 1 to 3, Figure 4 being a front elevation taken from the column engaging face of the shoe, Figure 5 being a top plan view, and Figure 6 being a sectional view taken in the plane indicated by the line 6—6 of Figure 5.

Figures 7 to 11 inclusive illustrate a modification of my invention, Figure 7 being a fragmentary side elevation of a railway car truck with the bolster and the associated friction means shown in section in approximately the vertical longitudinal plane bisecting the side frame, Figure 8 being a fragmentary top plan view of the structure shown in Figure 7, Figure 9 being a sectional view taken in the transverse vertical plane indicated by the line 9—9 of Figure 7, Figure 10 being a fragmentary top plan view of the bolster with the friction means dissociated therefrom, and Figure 11 being a sectional view taken in the plane indicated by the line 11—11 of Figure 10.

Figure 12 is a side elevation, partly in section, of a railway car truck illustrating another modification of my invention.

Describing my novel ride control truck in detail and referring first to the embodiment thereof illustrated in Figures 1 to 6 inclusive, the side frame comprises a compression member 2 and a tension member 4 merging adjacent each end thereof with a column 6 to define a bolster opening 8 having a widened upper portion 10 for a purpose hereinafter more fully described.

The tension member is of conventional box-section with the top chord thereof affording a seat at 12 (Figure 1) for the bolster supporting coil springs diagrammatically indicated at 14, 14 (Figures 1 and 2). The tension member is formed in the usual manner with an upstanding flange 16 on the inboard and on the outboard side thereof to afford convenient confining means 30 for the lower ends of the springs 14, 14. The upper ends of said springs afford a seat as at 18 (Figure 1) for the bolster generally designated 20, said bolster being of box-section with a pocket 22 in each side thereof, said pocket being defined by inboard and outboard webs 24 and 26 and by the rear web 28 affording a diagonal or wedge surface 30, as best seen in Figure 3, for cooperation with the associated friction shoe. It will be noted that the web 28 is slotted as at 32 adjacent its juncture with the bottom wall 34 of the bolster for the reception of a bolt and nut assembly affording actuation of the associated friction shoe, as hereinafter more fully described.

The bolster 20 is provided at each side thereof with inboard and outboard guide lugs or gibs 36 and 38, and it will be noted from a consideration of Figure 1 that the outboard gibs 38, 38 are of less depth than that of the widened upper portion 10 of the bolster opening whereby the bolster may be elevated in said opening and removed

therefrom while the bolster and the associated friction means remain in normal assembled relationship.

A friction shoe, generally designated 40, is disposed in each pocket 22 and one of said shoes is shown in detail in Figures 4 to 6 inclusive. It will be apparent from a consideration of these figures that the shoe is a casting cored away as at 42, 42 to lighten the same, and said shoe is provided on the front face thereof with a friction surface 44 for engagement as at 46 (Figures 2 and 3) with the adjacent column mounted wear plate 48, and said shoe comprises on the opposite face thereof a wedge surface 50 (Figure 6) for complementary engagement as at 52 (Figure 3) with the wedge surface 30 of the adjacent web 28 of the bolster. It will be seen from a consideration of Figure 3 that the wedge surface 50 of the shoe is crowned to afford a rocking action thereof against the surface 30. A substantially vertical opening 54 extends through the shoe 40 for the reception of an associated bolt and nut assembly 56, the opening 54 being square at the top thereof as at 58 to afford an interlock with the head of the bolt which is afforded a seat as at 60 against a shoulder formed within the opening 54.

Sleeved over the bolt is a spring 62, here shown as a coil spring and seated as at 64 against the bottom of the bolster. The bolt also carries a spring plate 66 for abutment with the opposite end of the spring 62, and a nut 68 is threaded on the lower end of the bolt to afford adjustable compression of the spring 62 against the bottom of the bolster. It will be understood that friction will be developed at 46 between each shoe and the associated wear plate during vertical movement of the bolster within the bolster opening, a greater amount of friction being developed on the upstroke of the bolster than on the downstroke thereof, inasmuch as the wedge surface 30 of the bolster slopes downwardly toward the adjacent column.

A modification of my invention is shown in Figures 7 to 11 inclusive wherein the side frame generally designated 102 is substantially the same as that shown in Figure 1, said frame including the spaced columns 104, 104 partially defining the bolster opening 106 having a widened upper portion 107 to permit removal of the bolster and the associated friction means from the top of the bolster opening substantially as in the previous embodiment of my invention. Seated on the side frame are the bolster supporting coil springs, diagrammatically indicated at 108, 108, and affording support as at 110 for the bolster, generally designated 112, said bolster being shown in detail in Figures 10 and 11 and being a box-like structure having the top and bottom walls 114 and 116 merging with spaced inboard and outboard transverse walls 118 and 120, the top wall 114 having a downwardly offset portion 122 (Figures 7 and 11) intermediate the walls 118 and 120 to define therewith a recess 124 for a purpose hereinafter described.

A spring seat 126 is formed on the bottom surface of the offset portion 122 and said offset portion is provided with an opening 128 therethrough centrally of said seat. The bottom wall 116 of the bolster is provided with an opening 130 aligned with the seat 126. At each side of the bolster is a diagonal wall 132 merging with the offset 122 of the top wall 114 and sloping downwardly and outwardly to merge with the bottom wall 116 of the bolster, each diagonal wall

132 presenting a wedge surface 134 for complementary engagement with an associated friction shoe, as hereinafter described. The bolster also comprises a side wall 136 at each side thereof and an intermediate longitudinal rib 138, substantially parallel with said side wall, and on each side of said bolster are inboard and outboard gibs 140 and 142 for interlocking engagement with the adjacent column 104 as in the previous embodiment of my invention, the outboard gibs 142, 142 being of less depth than the widened upper portion 107 of the bolster opening, as in the previous embodiment, to permit elevation and removal of the bolster from the top of the bolster opening together with the associated friction means.

At each side of the bolster is disposed a friction shoe generally designated 144, said shoe being generally similar to that shown in Figures 4 to 6 inclusive and comprising on one side thereof a friction face for engagement at 146 with the adjacent column mounted wear plate 148, and on the opposite side thereof said shoe is provided with a wedge surface for complementary engagement with the surface 134 on the adjacent wall 132 of the bolster. As may be noted in Figure 7, the wedge surfaces of the shoes are crowned to afford a rocking action thereof against the surfaces 134, 134. Each shoe is provided with a recess 150 on the top thereof for the reception of the adjacent end of an actuating plate 152, and the shoe is provided with a crowned abutment surface 154 (Figure 7) for engagement with said plate 152. It may be noted that each shoe is cored away as at 156 to lighten the same.

A coil spring 158 extends through the opening 130 in the bottom wall of the bolster and is seated at its upper end against the spring seat 126, the lower end of said spring bearing against a plate 160 carried by a bolt and nut assembly 162 sleeved within the spring 158, the bolt having a head 164 seated against the plate 152 and interlocked therewith by means of spaced lugs 166, 166 formed on said plate.

It will be understood that the bolt and nut assembly 162 may be tightened to afford adjustable compression of the spring 158, reaction of said spring being transmitted by the bolt and nut assembly to the plate 152 which bears against the surfaces 154, 154 on the friction shoes to urge the same downwardly and outwardly into engagement at 146, 146 with the adjacent column mounted wear plates, as heretofore described. When it is desired to remove the bolster from the bolster opening 106 during a quick wheel change, the bolt and nut assembly 162 may be loosened to release the pressure against the friction shoes, and thereafter the bolster may be elevated in the bolster opening and removed from the widened portion 107 thereof, substantially as in the previously described embodiment.

Another modification of my invention is shown in Figure 12 wherein the side frame comprises the compression member 202, the tension member 204, and a column 206 merging therewith adjacent each end of the frame to define a bolster opening 208. Seated at 207 on the side frame are the bolster supporting coil springs diagrammatically indicated at 210, said springs affording a seat as at 212 for the bolster, generally designated 214, said bolster being substantially identical with that disclosed in Figures 1 and 2 and comprising at each side thereof the diagonal web 216 affording a wedge surface 218 for complementary engagement with a wedge surface on an

associated friction shoe, generally designated 220, said shoe having a front friction face in frictional engagement as at 222 with the adjacent column mounted wear plate 224. On the top thereof the shoe is provided with a recess 226 for the reception of a coil spring 228 seated as at 230 against the shoe and in abutment at the opposite end with a spring plate 232 carried by the bolt and nut assembly 234, said assembly being engaged as at 236 with the bottom of the bolster and extending upwardly through a slot 238 therein and through an opening 240 in the shoe 220.

It will be understood that the bolt and nut assembly may be tightened to adjust the compression of the spring 228 against the shoe, and likewise, the bolt and nut assembly may be loosened during assembly and disassembly of the bolster and friction shoes with respect to the side frame. It may be noted that the bottom chord of the box-section compression member is cored away at 242 to afford clearance for the bolt and nut assembly during vertical oscillation of the bolster and to facilitate assembly and disassembly of the bolster with the side frame. It may also be noted that in this, as well as in the previous embodiments of my invention, the wedge surface of the friction shoe is crowned to afford a rocking action thereof against the bolster wedge surface 218.

It is to be understood that I do not wish to be limited by the exact embodiments of the device shown which are merely by way of illustration and not limitation as various and other forms of the device will, of course, be apparent to those skilled in the art without departing from the spirit of the invention or the scope of the claims.

I claim:

1. In a railway car truck, a side frame having spaced columns and an intervening bolster opening, a spring group on said frame in said opening, a bolster member supported from said group and having a pocket in at least one side thereof, and a wedge surface in said pocket sloping toward the adjacent column, a wedge member in said pocket in engagement with said surface and in frictional engagement with said column along a surface extending transversely of said frame, a substantially vertical coil spring in said opening and seated against one of said members, a substantially vertical bolt sleeved within said spring, a spring plate on one end of said bolt in abutment with said spring, means operatively connecting the other end of said bolt with the other of said members, and a nut on said bolt for adjustably compressing said spring plate against said spring, said bolt extending through an opening in said bolster member and being housed therein for a substantial portion of the length of said bolt.

2. In a railway car truck, a side frame having spaced columns and an intervening bolster opening with a widened upper portion, a spring group on said frame in said opening, a bolster supported from said group, said bolster having wedge means at opposite sides thereof, friction shoes in wedge engagement with respective wedge means and in frictional engagement with respective columns, resilient means in said bolster opening and compressed against the underside of a wall of said bolster, and means connecting the bottom of said resilient means with the tops of said shoes, said bolster having inboard and outboard gibs for interlocking engagement with each column, the outboard gibs being of less depth than said widened upper portion of said bolster opening whereby the bolster may be elevated therein and re-

moved therefrom while said friction shoes and resilient means remain in normal assembled relationship with the bolster.

3. In a railway car truck, a side frame having spaced columns and an intervening bolster opening, a spring group on said frame in said opening, a bolster member supported from said group and having a wedge surface at each side thereof sloping downwardly toward the adjacent column, a friction member in engagement with said surface and in frictional engagement with the adjacent column along a flat surface lying in a plane substantially parallel with the longitudinal axis of said bolster member, resilient means in said bolster opening, said resilient means being independent of said spring group and being compressed against one of said members, substantially vertical rigid means engaged with said resilient means, means operatively connecting said rigid means with the other of said members for transmitting reaction of said resilient means thereto, said rigid means extending vertically through an opening in said bolster member and being partially housed therein, and means associated with said rigid means for adjusting the compression of said resilient means.

4. In a railway car truck, a side frame having spaced columns and an intervening bolster opening, a spring group on said frame in said opening, a bolster member supported from said group and having a pocket in at least one side thereof, and a wedge surface in said pocket sloping downwardly toward the adjacent column, a wedge member in said pocket in engagement with said surface and in frictional engagement with said column along a flat substantially vertical surface lying in a plane approximately perpendicular to the plane of said frame, a substantially vertical coil spring in said opening and seated against one of said members, a substantially vertical bolt sleeved within said spring, a spring plate on one end of said bolt in abutment with said spring, means operatively connecting the other end of said bolt with the other of said members, and a nut on said bolt for adjustably compressing said spring plate against said spring.

5. In a railway car truck, a side frame having spaced columns and an intervening bolster opening, a spring group on said frame in said opening, a bolster supported from said group and having wedge surfaces at opposite sides thereof sloping downwardly toward respective columns, friction shoes in engagement with respective of said surfaces and in frictional engagement with respective columns, resilient means in said opening and independent of said group, said means being compressed against a downwardly facing surface on said bolster, and means for adjustably compressing said resilient means, said compressing means including substantially vertical rigid means extending through said bolster and operatively connected to said shoes for transmitting reaction of said resilient means thereto.

6. In a railway car truck, a side frame having spaced columns and an intervening bolster opening, a spring group on said frame in said opening, a bolster supported on said group and having wedge surfaces at opposite sides thereof sloping downwardly toward respective columns, friction shoes engaged with respective of said surfaces and in frictional engagement with respective columns, a plate extending transversely of said bolster and bearing against the shoes at opposite sides thereof, a spring partially housed within said bolster, said spring being seated at one end

thereof against a downwardly facing surface on said bolster, and means for compressing said spring, said means including a rigid member connected to the opposite end thereof and connected to said plate.

7. In a railway car truck, a side frame having spaced columns and an intervening bolster opening, a spring group on said frame in said opening, a bolster member supported from said group and having a wedge surface at each side thereof sloping downwardly toward the adjacent column along a surface extending transversely of said frame, a friction member in engagement with said surface and in frictional engagement with the adjacent column, resilient means in said bolster opening, said resilient means being independent of said spring group and being compressed against one of said members, and substantially vertical rigid means engaged with said resilient means and with the other of said members to transmit reaction of said resilient means thereto, said rigid means extending vertically through said bolster member and being partially housed therein.

8. In a railway car truck, a side frame having spaced columns and an intervening bolster opening, a spring group on said frame in said opening, a bolster supported on said spring group and having wedge surfaces at opposite sides thereof sloping downwardly toward the adjacent columns, friction shoes in complementary engagement with respective wedge surfaces and in frictional engagement with respective columns, and actuating means for each shoe comprising a spring seated against the bottom of said bolster and depending therefrom, a bolt and nut assembly extending upwardly through a slot in said bolster and interlocked with said shoe, and a spring plate carried by the lower end of said assembly for abutment with the lower surface of said spring.

9. In a railway car truck, a side frame having spaced columns and an intervening bolster opening, a spring group on said frame in said opening, a bolster supported from said group, said bolster having wedge means at opposite sides thereof, friction shoes in wedge engagement with respective wedge means and in frictional engagement with respective columns, resilient means in said bolster opening and compressed against a wall of said bolster, and means connecting the bottom of said resilient means with said shoes, said connecting means comprising rigid means carrying abutment means for the bottom of said resilient means, and a connection between said rigid means and the tops of said shoes.

10. In a railway car truck, a side frame having spaced columns and an intervening bolster opening, a spring group on said frame in said opening, a bolster supported from said group and having wedge surfaces at opposite sides thereof sloping downwardly toward respective columns, friction shoes in engagement with respective of said surfaces and in frictional engagement with respective columns, resilient means in said opening and independent of said group, said means being compressed against a downwardly facing surface on said bolster, and means for adjustably compressing said resilient means, said compressing means being operatively connected to the tops of said shoes for transmitting reaction of said resilient means thereto.

11. In a railway car truck, a side frame having spaced columns and an intervening bolster opening, a spring group on said frame in said opening, a bolster member supported from said group

and having a wedge surface at each side thereof sloping downwardly toward the adjacent column, a friction member in engagement with said surface and in frictional engagement with the adjacent column along a surface extending transversely of said frame, resilient means in said bolster opening, said resilient means being independent of said spring group and being compressed against one of said members, and substantially vertical rigid means operatively associated with said resilient means and with the other of said members to transmit reaction of said resilient means thereto.

12. In a railway car truck, a side frame having spaced columns and an intervening bolster opening, a spring group on said frame in said opening, a bolster supported on said group and comprising wedge surfaces at opposite sides thereof sloping downwardly toward respective columns, friction shoes in engagement with respective of said surfaces and in frictional engagement with respective columns along flat vertical surfaces lying in respective planes approximately perpendicular to the longitudinal plane of said frame, and actuating means for each shoe comprising a spring seated thereagainst and a bolt and nut assembly engaged with the bottom of said bolster and the top of said spring, said bolt and nut assembly extending vertically through a slot in said bolster and through an opening in said shoe.

13. In a bolster for a railway car truck, a box-like member having top and bottom walls and spaced transverse walls merging therewith, said top wall having a downwardly offset portion intermediate said transverse walls, and oppositely sloping diagonal walls merging with said offset portion and said bottom wall at opposite sides of the bolster, a spring seat on the bottom of said offset portion, an opening through said portion centrally of said seat, and an opening through said bottom wall in alignment with said seat and adapted for the reception of an associated spring.

14. In a bolster for a railway car truck, a box-like member having top and bottom walls and spaced transverse walls merging therewith, said top wall having a downwardly offset portion intermediate said transverse walls and defining therewith a recess for the reception of actuating means for an associated friction absorbing device, and oppositely sloping diagonal walls merging with said offset portion and said bottom wall at opposite sides of the bolster, said diagonal walls presenting wedge surfaces for cooperation with associated friction shoes.

15. In a railway car truck, a side frame having spaced columns and an intervening bolster opening, a spring group on said frame in said opening, a bolster supported from said group, said bolster having wedge means at opposite sides thereof, friction shoes in wedge engagement with respective wedge means and in frictional engagement with respective columns, resilient means in said bolster opening and compressed against a wall of said bolster, and means connecting the bottom of said resilient means with said shoes.

16. In a railway car truck, a side frame having spaced columns and an intervening bolster opening, a spring group on said frame in said opening, a bolster supported from said group, said bolster having wedge means at opposite sides thereof, friction shoes in wedge engagement with respective wedge means and in frictional engagement with respective columns, resilient means compressed against the underside of a

wall of said bolster, and means supporting the bottom of said resilient means from said shoes.

17. In a railway car truck, a side frame having spaced columns and an intervening bolster opening, a spring group on said frame in said opening, a bolster member on said group having a wedge surface on at least one side thereof, sloping downwardly toward the adjacent column, a friction shoe member engaging said surface and also engaging said adjacent column along a surface extending transversely of said frame, and actuating means for said shoe member comprising resilient means in said bolster opening between said columns compressed against one of said members, a substantially vertical bolt and nut assembly connected to said resilient means, and means affording an operative connection between said assembly and the other of said members.

18. In a railway car truck comprising a side frame including spaced columns and a bolster member spring-supported from said frame between said columns, the combination of a wedge member in wedge engagement with said bolster member and in frictional engagement with the adjacent column along a surface extending transversely of the frame, resilient means compressed against one of said members, and vertical means extending through both of said members for transmitting reaction of said resilient means to the other of said members.

19. In a railway car truck comprising a side frame including spaced columns and a bolster member spring-supported from said frame between said columns, the combination of a wedge member in wedge engagement with said bolster member and in frictional engagement with the adjacent column along a surface extending transversely of the frame, resilient means compressed against one of said members, and vertical means extending through said members for transmitting reaction of said resilient means to the other of said members, said resilient means being housed for the major portion of its length within the bolster member.

20. In a railway car truck comprising a side frame including spaced columns and a bolster member spring-supported from said frame between said columns, friction means including friction elements in wedge engagement with said bolster and in frictional engagement with said columns, resilient means compressed against abutment means on the bolster, and means for transmitting reaction of said resilient means to said elements including a member extending longitudinally of said frame and operatively engaged with said elements.

21. In a railway car truck comprising a side frame including spaced columns and a box-section bolster resiliently supported from said frame between said columns, the combination of friction shoes in wedge engagement with said bolster and in frictional engagement with said columns, resilient means compressed against downwardly facing abutment means on the top wall of said bolster, and means for transmitting reaction of said resilient means to said shoes including a rigid member extending longitudinally of said frame and operatively engaged with said shoes.

22. In a railway car truck comprising a side

frame including spaced columns and a bolster spring-supported from said frame between said columns, the combination of friction means including shoes in wedge engagement with said bolster and in frictional engagement with respective columns along surfaces approximately parallel with the longitudinal axis of said bolster, resilient means compressed against the tops of said shoes, and vertical means for transmitting reaction of said resilient means to said bolster comprising rigid members extending through portions of said bolster and respective shoes for connection to respective resilient means.

23. In a railway car truck comprising a side frame including spaced columns and a bolster spring-supported from said frame between said columns, the combination of friction shoes in wedge engagement with wedge faces on said bolster and in frictional engagement with respective columns along substantially vertical surfaces approximately parallel to the longitudinal axis of said bolster, resilient means compressed against upwardly facing abutment means on said shoes, and means for transmitting reaction of said resilient means to said bolster comprising bolt and nut assemblies connected thereto and to said resilient means, each of said bolt and nut assemblies extending through an opening in said bolster interrupting the associated face.

24. In a railway car truck comprising a side frame including spaced columns and a bolster spring-supported from said frame between said columns, the combination of a friction shoe in frictional engagement with the adjacent column along a surface extending approximately parallel with the longitudinal axis of the bolster, said shoe being in wedge engagement with said bolster, resilient means compressed against upwardly facing abutment means on said shoe and a rigid member extending through overlapping portions of said shoe and said bolster for transmitting reaction of said resilient means thereto.

25. In a railway car truck, a side frame including spaced columns, a spring group supported by said frame, a bolster supported by said group between said columns, a friction shoe having a wedge face in complementary engagement with a wedge face on said bolster, said shoe being in frictional engagement with the adjacent column along a surface approximately perpendicular to the longitudinal plane of said frame, resilient means compressed against said shoe, and a bolt and nut assembly operatively connected to said resilient means and to said bolster, said assembly extending through openings in said shoe and said bolster interrupting said faces.

26. In a railway car truck comprising a side frame including a column and a bolster member spring-supported from said frame adjacent said column, the combination of friction means including a shoe member in wedge engagement with the bolster member and in frictional engagement with said column along a surface extending transversely of said frame, resilient means compressed against abutment means on one of said members, and means for transmitting reaction of said resilient means to the other of said members comprising rigid vertical means extending through overlapping portions of said members.

LEO A. LEHRMAN.
